UNITED STATES PATENT OFFICE.

SAMUEL O. EDMONDS, OF NEW YORK, N. Y., ASSIGNOR TO A. B. DICK COMPANY, OF CHICAGO, ILLINOIS, A CORPORATION OF ILLINOIS.

PRINTING-MACHINE.

1,126,622.

Specification of Letters Patent. Patented Jan. 26, 1915.

Application filed December 22, 1909. Serial No. 534,443.

To all whom it may concern:

Be it known that I, SAMUEL O. EDMONDS, a citizen of the United States, residing at New York, in the county and State of New York, have invented certain new and useful Improvements in Printing-Machines, of which the following is a specification.

This invention relates to printing machines of the type adapted particularly for use in offices and for operation by unskilled persons in making multiple copies of letters, circulars and the like, especially letters and circulars printed in imitation of type-written work.

The invention is directed to the provision of a printing machine having means for printing names and addresses upon the letters or circulars printed thereby and for this purpose is arranged to utilize a plurality of type-plates each adapted to print a name and address upon one of the letters or circulars.

In accordance with the invention, a machine is employed preferably of that character in which is used a flat type-form and a pressure-roller adapted to rotate and to move bodily over the form of type, an ink ribbon being provided extending between the type-form and the impression sheet over-lying the same. The support for the type-form is such as to provide a groove extending across the type-form and through which a line of type-plates may be moved one after another. These type-plates may be of such size that a plurality of them may be in the groove at one time but means are provided whereby only one of the type-plates will be effective in each printing operation. Thus the type plates may normally be out of printing position in their passage through the groove and mechanism provided for raising one of the type-plates in the groove and holding it in an elevated position during the printing operation. The several type-plates may be separated from one another or, if desired, all of the type-plates may be connected together so as to form a tape. In either case suitable mechanism is provided for feeding the type-plates across the groove one step for each printing operation of the machine, and in case disconnected type-plates are employed the groove may be so formed that the movement of any plate will cause the plates ahead of it to be correspondingly pushed along.

I have illustrated the preferred embodiment of my invention in the accompanying drawings in which—

Figure 1 is a plan view of the machine broken away in part. Fig. 2 is a transverse section of same on line 2—2 of Fig. 1, Fig. 3 is a detail sectional view on line 3—3 of Fig. 1, Fig. 4 is a detail view on line 4—4 of Fig. 2, the hopper being removed to show the underlying parts, Fig. 5 is a view corresponding to Fig. 2 but illustrating a modification of the invention and Fig. 6 is a plan view of a portion of the mechanism illustrated in Fig. 5.

Referring first to Figs. 1 to 4 inclusive, the machine consists of a base A on which are mounted side frames B, B' between which is mounted a support C carrying the type-form c, the latter being locked in a chase c'. An ink ribbon D overlies the printing faces of the type, this ribbon having its ends wound upon spools d mounted for rotation at opposite ends of the type-form. At one end of the machine is a shaft E having sprocket wheels secured to its ends and at the opposite end of the machine two sprocket wheels are similarly mounted upon the side-frames; two chains e run upon these sprocket-wheels, one chain adjacent to each side-frame of the machine. A pressure-roller F is mounted upon a shaft the ends of which are received in bearings carried by these chains e and this pressure-roller is adapted to move in one direction over the type-form and in coaction with the type and in the other direction on the opposite side of the type-form and the support therefor in order to return the pressure-roller to its initial position. The shaft E may be actuated in any suitable manner as for instance by the operating handle shown at e' and a fly-wheel e² may be provided upon the shaft E.

Referring now to the parts of the printing mechanism to which my invention more especially relates, there is provided a groove extending across the type-form; for this purpose the side members of the chase have grooves cut therein and a piece of furniture is locked in the chase with the type either having a groove formed in the upper face thereof or being of less height than the pieces of furniture or the type adjacent thereto.

In the drawings I have shown a piece of

furniture G having a groove cut in its upper face. This groove, in the figure referred to, is shown as of one depth for a portion of its length and of a greater depth for the remainder of its length, as is shown in Fig. 2, so as to provide a shoulder *g*. When a type-plate passes beyond the shoulder *g* it drops to a lower level such that the type-form thereon will not coact with the pressure-roller F to print. This feature of my device, however, is not claimed herein, another means for causing the type-plates to be successively brought into operative position being described hereafter. Mounted upon the side frame B is a receptacle H adapted to receive a plurality of type-plates *h* each having type thereon representing a name and address. The bottom of this receptacle consists of a sliding plate *h'* slotted at one end thereof so as to provide a space in which a stationary supporting member *h''* is received, this being carried by the side frame of the machine. A spring *h'''* normally holds sliding plate *h'* in the position in which it is shown in Figs. 2 and 4, this spring being attached at one end to an extension *h''* of the side frame B and at the other end to a pin depending from the plate *h'*. On the other side of the plate *h'* is formed a rack with teeth to be engaged by a mutilated gear *i'* carried by a shaft I. On this shaft is secured a bevel gear *i''* meshing with a similar gear *i'''* secured to the shaft E. Pivottally mounted upon the plate *h'* are two pawls J each of which is pressed upwardly by a leaf-spring *j*. On the opposite side of the machine is any suitable device for receiving the type-plates after they have been used in printing; in the present instance I have shown a chute K leading to a receptacle *k*.

When the machine is operated, the handle *e'* is turned to cause the pressure-roller F to travel over the type-form and to print by pressing a sheet into engagement with the printing faces of the type *c* through the ink ribbon D and thereafter to be returned on the opposite side of the type-form and type-support. During each excursion of the roller F the shaft I will be caused to make one revolution by the gears *i'', i'''*. During such revolution the shaft I turns the gear *i'* and the latter moves the plate *h'* to the right in Fig. 2; as it does so the hangers J carried by the plate *h'* engage the lowermost type-plate *h* in the receptacle H and move the same with the plate *h'* over the supporting plate *h''*. After the type-plate has been moved beyond the edge of the receptacle H the gear *i'* disengages the rack *i* because of the mutilation of the gear and the plate *h'* is returned to its initial position by the spring *h'''*; then when the gear *i'* begins another rotation it again engages the rack *i* and actuates it as before so as to move

another type-plate *h* to the right in Fig. 2. This type-plate pushes the one before it farther along in the groove extending across the type-form and this type-plate which is so moved is carried into the printing position so that, on its next excursion, the roller F will coact with this type-plate and print from it upon the impression-sheet just as it prints from the type *c* which are locked in the chase. After this plate has been used in printing it will be forced along in the groove by the succeeding plate and will pass the shoulder *g* whereupon it will drop to a lower level at which level its type face will be too low to coact with the roller F. During succeeding operations this type-plate will be carried to the end of the groove extending across the type-form and will pass into the receiver *k*.

Referring now to Figs. 5 and 6, it will be seen that in this case the type-plates instead of being separate pieces are illustrated as being linked together so as to form a flexible belt or tape. In this case shaft I has a mutilated gear L thereon adapted to engage a gear *l* secured upon a shaft *l'* pivotally mounted in arms *l''* projecting from a side frame B'. The shaft *l'* carries two wheels *l'''* having arms the ends of which are adapted to enter the spaces between the adjacent type-plates *h*. Thus, during each rotation of shaft I the gear L will actuate the gear *l* and wheels *l'''* so as to feed the series of type-plates along in the groove extending across the type-form. As illustrated means may be employed as shown in Figs. 5 and 6 for raising bodily in the groove the type-plate from which it is desired to print. For this purpose the shaft I has secured thereto the cam M adapted to coact with a roller carried by a lever *m* pivoted at *m'*, to the arm *m''* projecting inwardly from the side frame B'. At its opposite end lever *m* carries a rod N to the upper end of which is secured a plate *n* forming the bottom of a portion of the groove extending across the type-form. A spiral spring *n'* may be provided coiled about the rod N. The cam M is so positioned upon the shaft I that it will actuate the lever *m* so as to raise the supporting-plate *n* just before the pressure-roller F comes over the type-plate supported by the plate *n*, and the distance which the plate *n* will be moved upwardly by the cam M will be sufficient to carry the type-plate thereon into position for proper coaction with the pressure-roller F. On the opposite side of the machine wheels may be provided similar to the wheels *l'''* adapted to guide the tape of type-plates into a suitable receptacle.

It will be noted that the means provided in connecting the several type-plates together is such that any plate in the tape may be moved upwardly in order to carry it into printing position without raising the two

plates adjacent thereto, as is shown in Fig. 5. After the sheet has been imprinted upon, the cam M will permit lever m to be returned to its initial position and spring n' 5 will force the plate n downwardly to its initial position.

Mechanism such as that just described for placing the address plates in operative position, is a feature of my invention, in connection with the use of address plates connected together, as illustrated in Figs. 5 and 6, or separate address plates fed into the groove in the manner described in connection with Figs. 1 to 4.

15 The guide-way for the type-plates extending across the type-form may be constructed in various manners. Thus it is only necessary to cut grooves in the side members of the chase and to use furniture in the 20 chase of such height as will form the groove positioned to continue and connect the slots in the chase. I prefer, however, to provide a special piece adapted to be inserted in the chase and to project through and beyond 25 the slot cut in the side members of the chase, these projecting portions serving to properly guide the type-plates into and out of the groove. In the present instance, I have shown the chase as consisting of a plate of 30 sheet-metal O to which the side and end members of the chase are secured, in which case the side members may be entirely cut away at the points where the groove for the type-plates crosses. At one side the 35 piece G is extended beyond the chase as shown at o in Fig. 4, and at the other side is a projection o' which coacts with the member h² secured to the side frame B to properly guide the type-plates.

40 In the accompanying drawings, I have shown the devices for printing the addresses as metallic plates having letters and figures raised thereon for printing the names and addresses. I wish it understood, however, 45 that the invention is in no way limited with respect to the character of the address plates. Instead of the metallic plates here shown, the address-plates may be stencil-plates of any suitable material, as waxed-50 paper, sheet-metal or other substance, or of such other character as may be desired.

Having now described my invention, what I claim as new therein and desire to secure by Letters Patent is as follows:—

55 1. In a printing machine, the combination of a support, a form of type thereon having a guide-way extending across the face of the same, a platen, means for moving the platen and type-form relatively to effect the 60 printing, a plurality of address-plates mov-

able in said guide-way, and means actuated automatically in accordance with the relative movement of the platen and type-form for raising the address-plate which is in a predetermined position in said guide-way 65 and holding said plate in operative position, substantially as set forth.

2. In a printing machine, the combination of a support, a form of type thereon having a guideway extending across the face of the same, a platen, means for moving the platen and type-form relatively, automatic feeding devices for feeding address-plates in said guideway, each plate having its printing face below the level of the printing face of 75 the form of type, and means operated automatically at definite intervals in the operation of the platen and type-form for raising the address-plate which is in a predetermined position in said guideway, substantially as set forth.

3. In a printing machine, the combination of a support, a form of type thereon having a guideway extending across the face of the same, a platen, means for moving the platen and type-form relatively, a plurality of address-plates pivotally connected in the form of a flexible tape and movable in said guideway, intermittently actuated feeding devices for feeding the tape, and means operated 85 automatically at definite intervals in the operation of the platen and type form for raising one plate of the portion of said tape in said guideway to operative position without raising the plates adjacent thereto, substantially as set forth.

4. In a printing machine, the combination of a support, a form of type thereon having a guideway extending across the face of the same, a platen, means for moving the platen 100 and type-form relatively, automatic feeding devices for feeding address-plates in said guideway, each plate having its printing face below the level of the printing face of the form of type, a movable plate constituting a part of said guideway adapted to be contacted by one of said address plates each 105 operation of the machine, and means for moving said plate at definite intervals in the operation of the platen and type form 110 for moving the address-plate contacted thereby into printing position, substantially as set forth.

This specification signed and witnessed this 18th day of December, 1909.

SAMUEL O. EDMONDS.
